(57) **CLAIM**

The ornamental design for a display screen or portion thereof with a graphical user interface for a search engine result page, as shown an described.

DESCRIPTION

FIG. 1 is a front view of a display screen or portion thereof with graphical user interface for a search engine result page according to a first embodiment of my design; and, FIG. 2 is a front view of a display screen or portion thereof with graphical user interface for a search engine result page according to a second embodiment of my design. The broken line showing the display screen or portion thereof forms no part of the claimed design. The broken lines showing portions of the graphical user interface form no part of the claimed design.

1 Claim, 2 Drawing Sheets
